[57] CLAIM

The ornamental design for a vehicle cab, substantially as shown.

DESCRIPTION

FIG. 1 is a side elevational view of the vehicle cab showing my new design;

FIG. 2 is a front elevational view thereof;

FIG. 3 is a side elevational view thereof opposite to that shown in FIG. 1;

FIG. 4 is a rear elevational view thereof; and

FIG. 5 is a top plan view thereof.
